UNITED STATES PATENT OFFICE.

GEORGE N. HEIN, OF SAN FRANCISCO, CALIFORNIA.

INVERTED HYPODERMIC SYRINGE.

Application filed March 19, 1926. Serial No. 96,014.

The invention relates to an inverted hypodermic syringe.

The object of the invention is to improve the construction of inverted hypodermic syringes and to provide a simple, practical and efficient inverted hypodermic syringe of strong durable and comparatively inexpensive construction in which the piston and the barrel may have either a ground 10 glass, metallic or an elastic packing fit.

A further object of the invention is to provide an inverted hypodermic syringe having a tubular or hollow piston and provided with means for maintaining the same 15 in proper position and for rendering it stationary to allow the barrel to reciprocally function on the same.

Another object of the invention is to enable in the larger hypodermic syringes of 20 the inverted type to reduce the amount of the frictionally contacting surface of the piston and in fact to enable a piston having a relatively short piston head to be provided with either a ground glass fit or an elastic 25 packing fit.

Another object of the invention is to equip inverted hypodermic syringes of the larger type with means for slidably guiding and steading the inner end of the barrel 30 to enable a short piston head to be employed.

With these and other objects in view the invention consists in the construction and novel combination and arrangement of parts hereinafter fully described, illustrated in 35 the accompanying drawings and pointed out in the claims hereto appended, it being understood that various changes in the form, proportion and minor details of construction may be resorted to without departing 40 from the spirit or sacrificing any of the advantages of the invention.

In the drawings:

Fig. 1 is a vertical sectional view of an inverted hypodermic syringe constructed in 45 accordance with this invention.

Fig. 2 is a horizontal sectional view of the same.

Fig. 3 is a longitudinal sectional view of 50 an inverted hypodermic syringe illustrating another form of the invention in which the piston is composed of a plurality of sections.

Fig. 4 is an enlarged detailed sectional view illustrating another form of joint and packing for the sections of the piston.

Fig. 5 is a longitudinal sectional view il-

lustrating another form of the invention in which the piston is composed of sections for the larger type of syringes.

Fig. 6 is a detailed sectional view illustrating an elastic packing for pistons of 60 large hypodermic syringes.

Fig. 7 is a longitudinal sectional view of 65 an inverted hypodermic syringe of the larger type equipped with slidable barrel guiding means.

Fig. 8 is a horizontal sectional view 70 through the holder or grip taken substantially on the line 8—8 of Figure 7.

Fig. 9 is a detail sectional view illustrating another form of stem.

Fig. 10 is a detail view illustrating the 75 construction of the resilient fingers shown in Fig. 7.

Fig. 11 is a detail view of the barrel of Fig. 1 shown in position for receiving a 75 medicament.

Referring particularly to Figures 1 and 2 of the drawings, the inverted hypodermic syringe which is designed for the smaller type of syringes subjected to excessive pressure comprises in its construction a metallic holder 1, a hollow tubular piston 2 and a barrel 3. The holder which may be varied in construction and which may be made of any suitable material is composed of spaced 80 sides and connecting upper and lower portions, the spaces between the sides of the holder exposing the hollow piston and the barrel which are preferably constructed of glass but which may be made of metal or 85 glass. The upper and lower portions 3 and 4 are circular and the lower portion which is preferably thickened as shown forms a seat for the tubular piston and is provided with interior screw threads 5 to be engaged 90 by a threaded portion 6 of the tubular piston whereby the piston is mounted upon the holder between the sides thereof in fixed 95 relation to the same. The holder is provided at its upper end with laterally projecting grips 7 which are preferably curved as shown to fit the fingers of the operator.

The hollow tubular piston is reduced at the lower end to form the threaded portion or shank and it is provided also at the lower 105 end with a reduced projecting nipple 8 adapted to receive a hypodermic needle and preferably provided with a tapered coiled spring 9 for positively holding the needle in place on the nipple. In practice the 110

needle will be interlocked with the nipple and the latter is preferably provided with an annular rib or enlargement 10 for engaging the upper coils of the spring. The piston which is designed in this form of the invention to have a ground glass or similar fit within the barrel is composed of an outer shell and an inner tube 11 which provides a bore or passage for the liquid contained within the barrel. The barrel 3 is preferably provided with an enlarged upper end or head 12 presenting a flat upper face and adapted to serve as a base for supporting the barrel in an upright position to serve as a container for the liquid to be injected into the patient by the hypodermic syringe. The ground glass barrel is telescopically placed over the hollow tubular piston and is introduced between the same and the holder and the barrel will be guided and a liquid and airtight joint is provided. In the form of the invention a perfect inverted hypodermic syringe is provided without the use of an elastic gasket. The ground glass fit extends the entire length of the barrel and a similar smooth fit is provided when the barrel and the hollow tubular piston are constructed of metal.

In order to prevent the barrel from accidentally dropping off the piston in the handling of the hypodermic syringe the latter is equipped with a friction device consisting of a curved plate or member 13 arranged exteriorly of the holder at the upper end thereof and provided with a protuberance 14 preferably formed by indenting the material of the plate 13 or bending a portion of the same at right angles and extending through an opening 15 in the holder and presenting a curved surface to and frictionally engaging the barrel as clearly illustrated in Figure 2 of the drawings. The curved plate 13 conforms to the configuration of the holder and is connected with the terminals of a coiled spring 16 encircling the holder as shown and yieldably maintaining the projection 14 in engagement with the barrel. The plate 13 is provided with perforations 17 and the ends of the coiled spring are secured in the said perforations.

In Figure 3 of the drawings is illustrated an inverted hypodermic syringe having a hollow tubular piston provided with a ground glass fit and composed of an upper section 18 and a lower section 19. The piston shown in Figure 3 is arranged within a metallic holder 20 constructed the same as that heretofore described but the holder may of course be made of any suitable material. The lower section of the piston is preferably constructed of metal and consists of a reduced stem portion provided at its lower end with a head 21 threaded to screw into the socket or opening 22 in the lower connecting portion of the holder 20. The said section 19 is provided with a nipple exten-

sion 23 and is equipped with a coiled needle holding spring 24 arranged on a nipple in the same manner as that described in Figure 1. The said lower section 19 which is provided with a longitudinal bore 25 has an enlarged upper end or head 26 provided with an interiorly threaded socket 27 to receive a threaded shank or portion 28 of the upper section 18 of the piston. The upper section 18 which is tubular and hollow is constructed of glass and consists of an outer shell and an inner tube 29 forming a passage for the liquid contents of the barrel 30 sliding telescopically over the upper section of the piston. The lower end of the upper section of the piston is provided with a tapered extension or nipple 31 which fits within a tapered extension 32 of the socket 27. The tapered extension of the socket presents inclined walls to the inclined surface of the nipple 31 and an air and liquid tight connection is provided. Instead of providing the tapered extension or nipple and the tapered portion of the socket a substantially cylindrical nipple 33 may be employed as illustrated in Figure 4 of the drawings. Nipple 33 which is provided with annular rib 34 receives an elastic packing 35 which engages a smooth cylindrical portion 36 of the socket 37 of the lower section 38 of the piston shown in Figure 4. The rib 33 causes an annular projection or rib to be formed exteriorly of the elastic packing for engaging the smooth portion 36 of the socket 37. An air and liquid tight connection is thus provided between the substance of the piston. A form of the piston shown in Figures 3 and 4 is for the purpose of reducing the area or length of the ground glass fit or compacting surface of the piston. This will enable a relatively long piston and barrel to be employed with only a relatively short ground glass surface on the piston. The same construction may of course be employed when the parts are made of metal and the contacting surface of the piston may be made relatively short in the same manner.

In Figure 5 of the drawing is illustrated a sectional piston for hypodermic syringes of the larger sizes composed of a lower section 39 and an upper section 40. The upper section is preferably constructed of glass and the lower section 39 may be made of either glass or metal. The upper section telescopically receives a barrel 41 and a relatively short ground glass surface is provided on the upper section of the piston to effect a liquid and air tight connection between the piston and the barrel. The lower end of the upper section is reduced to provide a threaded shank 42 which is received within an interiorly threaded socket 43 of the lower section 39 and the latter is provided with an upwardly extending stem 44 formed integral with the lower section and

received within a longitudinal opening 45 in the upper section. The stem and the lower section are provided with a bore 46 to form a passage for the liquid or other contents of the barrel 41 and the upper end of the stem may be tapered as shown at 47 to fit a tapered portion 48 of the opening 45. This will provide a tight fit but a tight fit may be effected by means of engaging the upper end of the stem with an inclined surface 49 as illustrated in Figure 9 of the drawings. In this figure the stem 50 is provided with a reduced upper end and the opening in the upper section 51 of the piston is provided with a conical portion which is engaged by the upper edge of the stem 50. Also as illustrated in Figure 6 of the drawings the upper section may be reduced as shown at 52 and provided with an annular rib 53 which is adapted to produce an annular enlargement exteriorly of an elastic gasket 54. The enlarged or distended portion of the gasket projects slightly beyond the side face of the piston for contact with the barrel of the syringe.

In Figures 7 and 8 of the drawings is illustrated a syringe of the larger type comprising a piston composed of upper and lower sections 55 and 56 adapted to be constructed of either glass or metal and preferably secured together by a threaded connection. A threaded connection as shown in this figure consists of a reduced threaded shank 57 which screws into an interiorly threaded socket 58. The shank is preferably formed on the lower end of the upper section of the piston and the socket is provided in the upper end of the lower section which has an integral upwardly extending stem 59 arranged in a longitudinal opening 60 in the upper section of the piston. The upper section is shown provided with an elastic gasket 61 arranged on a reduced upper portion 62 of the upper section 55 of the piston and having a projecting annular portion 63 formed by an annular rib 64 of the reduced upper end portion 62 of the piston. The elastic gasket may of course be omitted if desired and a ground glass fit may be employed instead of the gasket. The inner or lower end of the barrel is guided by a slidable guiding device comprising a hub 65 having an opening to receive the lower section of the piston and provided with a flange 66 upon which is mounted a plurality of resilient barrel engaging members 67 preferably consisting of approximately U-shaped fingers curved longitudinally at their upper portion to provide a flaring entrance to the guide. The fingers 67 may be constructed of any suitable resilient material and their outer or lower terminal portions are secured to the periphery of the flange 66 preferably in suitable recesses thereof as shown. The

resilient fingers are adapted to be distended to accommodate barrels of different diameters and the head or upper section may be removed and a head or section of a different diameter may be applied to the lower section 70 to fit the desired barrel. By this operation a variety of different sizes of barrels and pistons may be employed and in the operation of the hypodermic syringe the guide will maintain the lower end of the barrel in 75 proper position with relation to the piston. The piston is mounted in a suitable holder which in the form of the invention shown in Figure 7 consists of a hub 68 interiorly threaded at 69 to receive the lower threaded 80 end portion 70 of the lower section 56. The holder is provided with lateral extensions 71 which are preferably concave at the side faces to facilitate gripping and holding the piston. Any other suitable form of grip or 85 holder may be employed and the piston is provided at its lower end with a nipple 72 and with a needle holding spring 73. The bore 74 of the lower section forms a passage for the liquid or other contents of the barrel 90 and the upper end of the extension 59 forms a tight connection with the upper section of the piston preferably by being tapered as shown but any other form of joint or connection may of course be employed. 95

What is claimed is:

1. An inverted hypodermic spring comprising a piston having an enlarged upper portion or head provided with a packing at one end and having a guiding portion extending beyond the packing and a reduced lower portion or stem, a barrel telescopically fitted over the enlarged upper portion of the piston and guided by the same and a guide 100 slidably mounted on the reduced lower portion of the piston and receiving and guiding the lower end of the barrel. 105

2. An inverted hypodermic syringe comprising a piston having a longitudinal bore or passage and composed of an enlarged upper portion or head and a lower portion or rod, a barrel open at the lower end telescopically fitted over the enlarged upper portion or head and guided by the same and a guide 110 slidably fitted on and movable along the lower portion or rod of the piston and providing a seat for the lower end of the barrel and having means for slidably engaging the same. 115

3. An inverted hypodermic syringe comprising a hollow tubular piston having an upper enlarged portion or head and a lower portion or rod, a barrel slidably fitting the upper portion or head of the piston and a guide slidably mounted on the lower portion or rod of the piston and consisting of a hub 120 forming a seat for the lower end of the barrel and resilient fingers carried by the hub and yieldingly engaging the barrel. 125

4. An inverted hypodermic syringe com- 130

prising a hollow tubular piston composed of upper and lower sections provided with means for detachably connecting them together the upper section forming a head having a packing portion and an extended guiding portion and a lower section being of less diameter and constituting a piston rod, a stem extending from the lower section beyond the connecting means substantially through the upper section and provided with means for contacting therewith to form a tight joint and the barrel telescopically fitted over and guided by the upper section.

5. An inverted hypodermic syringe comprising a hollow tubular piston having an enlarged upper portion or head and a reduced lower portion or rod detachably connected together, the upper section having a packing portion and an extended guiding portion and, the lower section being provided with a stem extending beyond the detachable connection of the sections substantially through the upper section and engaging the same, a barrel slidable over the upper section and guided by the same and a holder secured to the lower section.

6. An inverted hypodermic syringe comprising a hollow tubular piston having an enlarged upper portion or head and a reduced lower portion or rod detachably connected together, the upper section having a packing portion and an extended guiding portion and, the lower section being provided with a stem extending beyond the detachable connection of the sections substantially through the upper section and engaging the same, a barrel slidable over the upper

section and guided by the same and a holder consisting of a hub secured to the lower end of the lower section of the piston and having laterally extending wings forming grips.

7. An inverted hypodermic syringe comprising a hollow tubular piston having an enlarged upper portion or head and a reduced lower portion or rod, the lower section being provided with a stem extending substantially through the upper section and engaging the same, a barrel slidable over the upper section and guided by the same, a holder consisting of a hub secured to the lower end of the lower section of the piston and having laterally extending wings forming grips, and a guide slidable on the lower section of the piston between the holder and the upper section and provided with means for forming a seat for the barrel and having yieldable means for retaining the barrel on the seat.

8. An inverted hypodermic syringe comprising a hollow tubular piston provided at the lower ends with screw threads and having a longitudinal bore extending centrally through the piston, said piston being also provided at its lower end with a projecting nipple enlarged at the inner portion and grooved thereat to receive a needle holding spring, an interiorly threaded holder receiving the piston and detachably engaging the screw threads thereof, and a barrel telescopically fitted over and guided by the piston.

In testimony whereof I have hereunto set my hand.

GEORGE N. HEIN.
